US00D826243S

(12) **United States Design Patent** (10) **Patent No.:** **US D826,243 S**
Broughton et al. (45) **Date of Patent:** **** Aug. 21, 2018**

(54) **DISPLAY SCREEN OR PORTION THEREOF WITH ANIMATED GRAPHICAL USER INTERFACE**

(71) Applicant: **Apple Inc.**, Cupertino, CA (US)

(72) Inventors: **Lee Broughton**, Santa Cruz, CA (US); **Kevin Will Chen**, Sunnyvale, CA (US); **Alan C. Dye**, San Francisco, CA (US); **Christopher P. Foss**, San Francisco, CA (US); **Heena Ko**, San Francisco, CA (US); **Stephen O. Lemay**, San Francisco, CA (US)

(73) Assignee: **Apple Inc.**, Cupertino, CA (US)

(**) Term: **15 Years**

(21) Appl. No.: **29/606,380**

(22) Filed: **Jun. 4, 2017**

(51) **LOC (11) Cl. 14-04**

(52) **U.S. Cl.**

USPC **D14/485**

(58) **Field of Classification Search**

(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof; and,

FIG. 3 is a third image thereof.

The outermost broken lines in the figures show a display screen or portion thereof, and form no part of the claimed design. The other broken lines in the figures show portions of the animated graphical user interface that form no part of the claimed design.

1 Claim, 3 Drawing Sheets
